UNITED STATES PATENT OFFICE.

JACOB BLOOM YEAGLEY, OF INDIANAPOLIS, INDIANA.

HYDRAULIC RAM.

SPECIFICATION forming part of Letters Patent No. 298,262, dated May 6, 1884.

Application filed October 20, 1883. (No model.)

To all whom it may concern:

Be it known that I, JACOB BLOOM YEAGLEY, a citizen of the United States, residing at Indianapolis, in the county of Marion and State 5 of Indiana, have invented certain new and useful Improvements in Hydraulic Rams or apparatus for raising water from wells having water-bearing strata of different hydrostatic levels; and I do hereby declare the following 10 to be a full, clear, and exact description of the invention, such as will enable others skilled in the art to which it appertains to make and use the same.

This invention relates to certain new and 15 useful improvements in hydraulic rams or apparatus for raising water from wells having water-bearing strata of different hydrostatic levels, and more particularly to improvements 20 upon my former patent, dated September 25, 1883, and numbered 285,774, and relating more especially to improvements in the manner 25 of the construction of some of the parts, and adapting the apparatus for the distribution of water, all as will be hereinafter fully described, and set forth in the claims hereto annexed.

Referring to the accompanying drawings, Figure 1 represents a vertical section through my improved apparatus after it has been 30 placed in the desired stratum; Fig. 2, an enlarged vertical section through my improved apparatus; Fig. 3, an enlarged detached view 35 of the upper and lower parts, which form the efflux fountain-pipe and the connections between the efflux valved chamber, valved air-chamber, and influx and supply pipes; Fig. 4, a detached view of the water-distributer.

Like letters of reference indicate like parts in the several figures.

In the drawings, A and B represent two 40 cast and grooved upper and lower parts or plates connected together by screws or bolts, with a suitable water-tight packing between their meeting faces. These grooved parts or 45 plates have an interior groove, which forms the efflux fountain-pipe D, and also the parts to which the influx fountain-pipe C, efflux valved chamber E, valved air-chamber F, and supply-tube G are connected by any suitable 50 screws or bolts. The parts A and B may be

cast in one piece. Through the bottom of lower part, B, is an opening, b', communicating with the groove b, that connects the valved air-chamber F with the supply-tube G. The opening b' is closed by a screw or other suitable plug or stop-cock attachment, b'; and the object of said opening b' is to drain out any sand or sediment that may gather in said groove b and valved air-chamber, by simply removing screw-plug, or opening stop-cock b', when the water in supply-pipe G will run out, and at the same time the sand and sediment will be washed out of the groove b and valved air-chamber. The valve e in efflux-chamber E is shaped like an inverted saucer, 65 with openings or slots e' in sides to let water flow through; and on outside edges, below and between each slot e', there is a small half-round opening, e'', to wash out the sand or sediment that may accumulate therein. This valve plays 70 freely in the efflux-chamber E, the openings letting through sufficient water to give the required velocity of the water-flow, and consequent required resulting momentum of the water. The wire chain or cord H has a weight, h, 75 (like the old-fashioned steelyard weight,) connected to it about five or six inches above its connection with the valve-stem, so that the apparatus is stopped by taking wire chain or cord in hand and, by lifting, close efflux cylinder or chamber by valve e, when the water-pressure on bottom of efflux-chamber valve e will hold it closed. Then the supply-pipe drainer 22 may be opened, if required, to prevent freezing of the water in said supply-pipe. 80 The apparatus is again set in motion by dropping the weight h on valve-stem, by means of wire chain or cord H, to push valve down, when the water will instantly begin to flow from the efflux valved chamber E, thus setting the apparatus in automatic operation. The weight h is then raised (by means of wire chain or cord) just high enough, so as not to interfere with the valve-stem in its automatic 85 upward and downward motion. The supply-pipe drainer 22 is then closed.

I represents a hydraulic distributer, to be screwed on supply-pipe G at the point g, and has a number of short tubes, i, provided with stop-cocks i'; and by means of pipes or hose 90

connected to said tubes *i* the water can be forced to any desired place by opening that one needed and closing the others.

By connecting any of the hose or pipes with 5 a or to a turbine or any water-motor wheel, there may be run not only light but heavy machinery in proportion to the size of my apparatus.

Construction and operation of my improved 10 apparatus: In Fig. 1 is shown a dug well into the first sand and gravel or any other water-bearing stratum, V, giving a low water-rise and good drainage, the water rising in well to the height Y Y. The influx fountain pipe or 15 tube C is now driven or sunk by boring or drilling through the clay stratum Z, or other stratum or strata impervious to water, into the second or any other water-bearing stratum, W W, giving the required hydrostatic rise in 20 fountain-pipe C above the water-rise in the well employed as a drain of the waste water from the apparatus. The fountain-pipe C may or may not be perforated at its lower end, terminating in cavity K, which cavity may usually 25 be formed by pumping out the finer sand before the apparatus is screwed on pipe C. This pipe C, as also supply-pipe G, efflux valved chamber E, and valved air-chamber F, should then be connected to the connected upper and lower parts, A and B. The water will now flow from pipe C through efflux-opening D by hydrostatic pressure, attempting to 30 reach the hydrostatic equilibrium of the fountain-head water supplying the stratum in which the fountain-pipe C terminates at its 35 lower end. Now, when the water has attained its greatest velocity through pipes CD, in seeking its hydrostatic level, the valve *e* will close the efflux-chamber E instantly, by being carried up by the current, and, by the sudden 40 stoppage of flow, water will be forced into the air-chamber, forcing up the valve *f*, which opens upward. The aperture through the bottom of air-chamber closed by said valve should 45 be perpendicularly over and nearly as large in area as the upper opening of the fountain-pipe C, in order to obtain the greatest possible 50 beneficial results, as shown by my experiments with this apparatus. When the current through pipe or opening D carries up the efflux-valve *e*, closing the efflux chamber or cylinder E, causing a sudden stoppage of flow through 55 said chamber or cylinder, the water, by force of its momentum in fountain-pipe C, has its greatest pressure against and beneath the air-chamber valve *f*, because it is in direct line with the flow of the water in and through the fountain-pipe C, even drawing a portion of the water out of pipe D and efflux valved chamber E, below the efflux-valve *e*, when closing 60 said efflux-chamber, caused by the rapid velocity of the water in fountain-pipe C, entering air-chamber. Thus it will be seen that the efflux-valve *e* does not fall wholly by its 65 own weight or specific gravity, but partly by the suction or partial vacuum formed in pipe

D and efflux-chamber E, below the valve *e*. The flow having thus expended its effective force or momentum against the resistance of the condensed valved air-chamber, the water 70 will again flow through pipe or opening D and efflux-chamber E, when the valve *e* will again close the aperture of the efflux-chamber E when the flow has attained its greatest velocity, which is almost instantly, as the flow 75 is in reality perpendicular, while the reaction, at the same time, cannot cause the water to throw itself back upon the reservoir, because said reservoir is full and curbed beneath pervious and impervious strata. By these 80 successive impulses, caused by the velocity of flow and momentum of the water, as above described, water is forced automatically in a steady stream through the supply-pipe G by the aid of the air-chamber, otherwise, without 85 the air-chamber, the water would issue from supply-pipe G spasmodically at each pulsation of the valve *e* in the efflux-chamber E, which pulsations have but little variations in the same apparatus attached to the same fountain-pipe C.

X X represent a suppositional height to which the water rises from the cavity K. Any two water-bearing strata, whether first and second, first and third, second and third, or 95 first and fourth, second and fourth, or any other combination of water-bearing strata (separated by a stratum or strata impervious to water) giving the greatest difference of hydrostatic levels, are employed. A difference 100 as low as two and one-half feet will automatically operate my improved apparatus successfully for ordinary purposes. Where any one of above-specified water-bearing stratum, or any other farther down, gives an Artesian 105 flow sufficiently high above the surface of the ground, then the apparatus may be screwed on Artesian-fountain pipe and the surface of the ground employed to drain off the waste water from the apparatus where water is required to be raised higher than the Artesian 110 fountain flow.

I have demonstrated, recently, that a difference of hydrostatic levels of from five to fifteen feet can be invariably found in this city 115 and adjacent country between the rise, in a dug well, into first water-bearing stratum and the rise from the second water-bearing stratum, when tubed through the water-rise in the dug well by means of the fountain-pipe C, and 120 wonderful results of power obtained with my improved apparatus by actual public demonstration, as above stated. The geological stratification of the earth's crust is such as to almost invariably find in any locality a difference of 125 hydrostatic levels in the water-bearing strata underlying the earth's surface, as explained above, to operate my improved apparatus.

Having thus fully described my invention, what I claim as new, and desire to secure by 130 Letters Patent, is—

1. In a hydraulic ram or apparatus for rais-

- ing water from wells having water-bearing strata of different hydrostatic levels, the combination, with an influx fountain-pipe, C, of the two-part castings A B, having a pipe, D, 5 groove b , efflux valved chamber E, and valved air-chamber F, said parts adapted to connect two water-bearing strata of different hydrostatic levels, substantially as and for the purposes herein shown and described.
- 10 2. In a hydraulic ram or apparatus for raising water from wells having water-bearing strata of different hydrostatic levels, the combination, with an influx fountain-pipe, C, of the parts A and B, having a pipe, D, the efflux valved chamber E, valved air-chamber F, and supply-pipe G, adapted to communicate with air-chamber, and all arranged to connect two water-bearing strata of different hydrostatic levels, substantially as and for the 20 purposes herein shown and described.
- 15 3. In a hydraulic ram or apparatus for raising water from wells having water-bearing strata of different hydrostatic levels, the combination, with an efflux-chamber, E, an air-chamber adapted to connect pipes C D, and the supply-pipe G, of the parts A and B, provided with groove b , opening b' , and plug or stop-cock attachment b^2 , substantially as and for the purposes herein shown and described.
- 25 4. In a hydraulic ram or apparatus for raising water from wells having water-bearing strata of different hydrostatic levels, the combination, with a valved air-chamber and influx and efflux pipes, of the efflux-chamber E, having an inverted saucer-shaped valve, e, 30 having the two series of openings $e e^2$, substantially as and for the purposes herein shown and described.
5. In a hydraulic ram or apparatus for raising water from wells having water-bearing strata of different hydrostatic levels, the combination, with a valved air-chamber and influx and efflux pipes, of the efflux-chamber E, having a valve, e, and connecting rope or chain, H, having a weight, h, substantially as 35 and for the purposes herein shown and described.
6. In a hydraulic ram or apparatus for raising water from wells having water-bearing strata of different hydrostatic levels, the combination of an influx fountain-pipe, an efflux fountain-pipe, said two pipes adapted to connect two (2) water-bearing strata of different hydrostatic levels, intermediate valved air-chamber, efflux valved chamber, supply-pipe, 50 and drainer 2 2, and a water-distributer having a series of pipes controlled by stop-cocks, substantially as and for the purposes herein shown and described.
7. The combination of an Artesian-fountain pipe, an efflux fountain-pipe with an efflux valved chamber, intermediate valved air-chamber adapted to connect efflux fountain-pipe and Artesian-fountain-pipe, and the supply-pipe G and parts A and B, provided with 55 groove b and plug or stop-cock attachment b^2 , substantially as and for the purposes herein specified.

In testimony whereof I affix my signature in presence of two witnesses.

JACOB BLOOM YEAGLEY.
